(57) **CLAIM**

The ornamental design of a symmetrical ornamental candle with reuleaux triangle cross section, substantially as shown and described.

DESCRIPTION

FIG. 1 is a perspective view of a symmetrical cylindrical candle having the new design, with cross-section in the shape of a Reuleaux triangle;

FIG. 2 is a top plan view of the symmetrical ornamental candle with reuleaux triangle cross section shown in FIG. 1, displaying the three-fold symmetry thereof;

FIG. 3 is a front view of the symmetrical ornamental candle with reuleaux triangle cross section shown in FIG. 1, displaying a rectangular cutout for the placing of a label, such as a Scriptural or seasonal message;

FIG. 4 is a left side view of the symmetrical ornamental candle with reuleaux triangle cross section shown in FIG. 1, the right side view being a mirror image thereof;

FIG. 5 is a rear view of the symmetrical ornamental candle with reuleaux triangle cross section shown in FIG. 1; and,

FIG. 6 is a bottom view of the symmetrical ornamental candle with reuleaux triangle cross section shown in FIG. 1.
